The ornamental design for an instrument panel for an automobile, as shown and described.

DESCRIPTION

FIG. 1 is a front elevational view of an instrument panel for an automobile in accordance with my new design;

FIG. 2 is a top plan view of the instrument panel in accordance with my new design of FIG. 1;

FIG. 3 is a bottom plan view of the instrument panel in accordance with my new design of FIGS. 1 and 2;

FIG. 4 is a right side elevational view of the instrument panel in accordance with my new design of FIGS. 1 to 3;

FIG. 5 is a left side elevational view of the instrument panel in accordance with my new design of FIGS. 1 to 4;

FIG. 6 is a front, left side perspective view of the instrument panel in accordance with my new design of FIGS. 1 to 5; and,

FIG. 7 is a front, right perspective view of the instrument panel in accordance with my new design of FIGS. 1 to 6.

The rear surfaces of the instrument panel depicted by broken lines in FIGS. 1 to 7 form no part of the claimed design. A second embodiment of our new design is a mirror image of the design shown in FIGS. 1 to 7.
